UNITED STATES PATENT OFFICE.

WILBER CYRUS ROSE, OF SPOKANE, WASHINGTON.

POMACE-CHUTE.

1,123,385.

Specification of Letters Patent.

Patented Jan. 5, 1915.

Application filed March 17, 1914. Serial No. 325,362.

To all whom it may concern:

Be it known that I, WILBER C. ROSE, a citizen of the United States, residing at Spokane, in the county of Spokane and State of Washington, have invented certain new and useful Improvements in Pomace-Chutes; and I do hereby declare the following to be a full, clear, and exact description of the invention, such as will enable others skilled in the art to which it appertains to make and use the same.

This invention relates to telescopic chutes for apple pumace and other similar substances; and it consists in the novel construction and combination of the parts hereinafter fully described and claimed whereby the supply of pomace to the chute is cut off automatically when the chute commences to descend, and whereby the action of the apparatus is regulated and controlled.

In the drawings, Figure 1 is an end view of a telescopic pomace chute and the devices for supplying it with pomace. Fig. 2 is a front view of the pomace chute, drawn to a larger scale. Fig. 3 is a cross-section through the chute, taken on the line $\alpha-\alpha$ in Fig. 2 and showing the chute extended and the doors open. Fig. 4 is a plan view of the chute, from below, showing the doors closed.

The chute is formed of sections 2 and 3, the lower section 3 being telescopic over the upper section 2 which is stationary, and which is secured to any suitable supporting frame 4. The sections of the chute are rectangular in cross-section and are a little larger at their bottom ends than at their tops so that the pomace may be discharged freely from them.

The apples or other fruit are formed into pomace in a grinding or comminuting machine 5 which is fed by means of an elevator 6. Any other approved means may be used for supplying pomace to the chute in carrying out this invention. The grinding machine and the elevator shown in the drawings are of any approved construction, and the grinding machine is arranged directly over the top of the chute and is driven continuously in any convenient way.

The elevator is preferably driven intermittently by means of a driving belt 7 and fast and loose pulleys 8 and 9. A belt-shifter 10 is provided, and when the belt 55 is shifted onto the loose pulley 9 the elevator stops, so that the supply of apples,

and consequently the delivery of pomace to the chute, is cut off for the time being.

The lower chute section 3 is normally held in a raised position by weights 12. Cords 14 are attached to the section 3 at one end and are led over guide sheaves 15 on the frame, and are connected to levers 16 which are pivoted to the frame by pins 17 and are arranged at opposite sides of the chute. The 60 weights 12 are placed in boxes 18 which are 65 slideable upon the levers 16 to various positions, so that the action of the weights may be adjusted with great accuracy to produce the best effect. The weights are adjusted 70 so that the slideable section 3 will descend automatically by gravity when a predetermined quantity of pomace has been delivered into the chute. This quantity of pomace is 75 the amount necessary to make one layer of cheese.

The slideable chute section 3 is provided with a pair of discharge doors 20 at its bottom end, which are pivoted or hinged to it by pins 21, and which close automatically 80 when the chute is empty. Handles 22 are pivoted or hinged to the upper part of the slideable chute section by pins 23, and these handles engage with stops 24 on the projecting end portions of the doors, and form 85 catches which hold the doors locked when in their closed positions.

The belt-shifter 10 is secured to a bar 25 which is slideable in guides 26 on the frame, and a trip-lever 27 is pivoted to the frame by 90 a pin 28. The trip-lever is preferably a bell-crank lever, but any form of lever mechanism which will operate the belt-shifter, can be used. One arm of the trip-lever 27 is connected to the bar 25 by pins 95 29, and its other arm is arranged in the path of a trip 30 which is carried by the slideable chute section 3. The trip 30 is preferably pivotally connected to the chute section by a pin 31 so that it can be placed out of 100 action whenever desired. A spring 32 is secured to the bar 25 and to the frame, and operates to move the bar 25 longitudinally and to place the belt on the loose pulley.

When sufficient pomace has been delivered to the chute to form one layer of cheese, the slideable chute section descends by gravity. The spring shifts the belt and cuts off the supply of pomace to the chute, by stopping the elevator, as soon as the trip 110 leaves the trip-lever. When the slideable section has descended to its full extent, the

attendants pull the handles or catches 22 outwardly, thereby unlocking the chute doors, and the pomace flows out by gravity. The doors close automatically as soon as the 5 pomace is discharged, and the weights then raise the slidable chute section. The attendants guide the chute section in its upward movement, by means of the handles, and then permit the handles to engage with 10 the stops on the doors so that they are locked.

The trip 30 operates the trip-lever as 15 the slidable section ascends, and effects the re-starting of the elevator, so that more 20 pomace is supplied to the chute. When the day's work is finished, or at any other desirable time, the trip is placed out of action so that the slidable chute section may be raised by the weights without starting the 25 elevator.

What I claim is:

1. The combination, with a discharge chute provided with a slidable lower section, 25 of mechanism for supplying material to the said chute, and trip mechanism operated by the slidable chute section and arranged to place the supply mechanism in operation automatically when the slidable section is raised.
2. The combination, with a discharge chute provided with a slidable lower section, 30 of mechanism for supplying material to the said chute, trip mechanism which holds the supply mechanism in operation when the slidable section is raised, and means for stopping the supply mechanism automatically when the slidable section descends.
3. The combination, with a discharge 35

chute provided with a slidable lower section, of a comminuting machine for forming 40 pomace arranged over the said chute and delivering into it, and trip mechanism operated by the said slidable section and arranged to stop the formation of pomace 45 automatically when the slidable section descends.

4. The combination, with a discharge chute provided with a slidable lower section, of a comminuting machine for forming 50 pomace which delivers into the said chute, supply mechanism for delivering material 55 to the comminuting machine, and trip mechanism operated by the said slidable section and arranged to place the supply mechanism automatically in operation when 60 the slidable section is raised and out of operation when it descends.

5. The combination, with a discharge chute provided with a slidable delivery section, of mechanism for supplying material 60 to the chute, a means for controlling the starting and stopping of the chute supply mechanism, a pivoted bell-crank lever having one arm operatively connected with the 65 said means, and a trip carried by the said delivery section and arranged to engage with the other arm of the bell-crank lever when the delivery section ascends and thereby start the chute supply mechanism.

In testimony whereof I have affixed my 70 signature in the presence of two witnesses.

WILBER CYRUS ROSE.
